(57) **CLAIM**

The ornamental design for a motorcycle fairing, as shown and described.

DESCRIPTION

FIG. 1 is a front elevational view of a motorcycle fairing showing my new design;

FIG. 2 is a rear elevational view thereof;

FIG. 3 is a left side elevational view thereof;

FIG. 4 is a right side perspective view thereof; and,

FIG. 5 is a left perspective view thereof showing the fairing as mounted upon a motorcycle shown in broken line.

The broken lines shown are for illustrative purposes only and form no part of the claimed design.
